(57) **CLAIM**

The ornamental design for an interior for a vehicle, as shown and described.

DESCRIPTION

FIG. 1 is a front perspective view of the interior for a vehicle showing my design;

FIG. 2 is a front elevation view thereof;

FIG. 3 is a right side view thereof;

FIG. 4 is a rear elevation view thereof;

FIG. 5 is a left side view thereof, with the right and left side views being opposite to one another;

FIG. 6 is a top plan view thereof; and,

FIG. 7 is a bottom plan view thereof.

Portions of the interior for a vehicle shown in broken lines form no part of the claimed design.
